UNITED STATES PATENT OFFICE

FRANK J. VINCENT, OF LITTLE FALLS, NEW YORK

BAT

Application filed February 13, 1929. Serial No. 339,702.

This invention relates to bats for use in upholstering and the like.

In the upholstering of seats and cushions and particularly of chair and automobile seats and backs, it is customary to put over the springs one or more layers or bats, and the upholstery covering is then placed over the bats. Cotton bats have been customarily used heretofore for this purpose, but they are not particularly elastic or strong in tensile strength, and frequently it has been necessary to stitch the cotton bat to burlap or other fabric which is placed over the coils or springs in order to prevent the punching of holes in the cotton bats by the coils or springs. If the cotton bat were reinforced with paper or the like, in order to give it tensile strength, it would be inelastic and could not accommodate itself to undulations in the surface covered thereby without formation of wrinkles or creases which would be objectionable.

An object of the invention is to provide an improved bat of this type, which will have maximum strength; which will be somewhat elastic; which will accommodate itself to undulations in a surface or object covered without the formation of ribs or ridges; which may be used without a burlap or other fabric back; which may be easily made in various sizes, and which will be relatively simple and inexpensive.

A further object of the invention is to provide an improved method of making a bat which will accomplish the above objects.

Various other objects and advantages will be apparent from the following description of an embodiment of the invention, and the novel features will be particularly pointed out hereinafter in connection with the appended claims.

In the accompanying drawing:—

Fig. 1 is a perspective illustrating one of the steps in the manufacture of one of the improved bats;

Fig. 2 is a plan of a portion of one of the component bats;

Fig. 3 is a transverse, sectional elevation of the same;

Fig. 4 is a plan of a portion of an improved

bat during an intermediate step in its manufacture;

Fig. 5 is a transverse section of the same;

Fig. 6 is a perspective of a portion of the same, partially folded to indicate the manner in which it is folded; and

Fig. 7 is a similar perspective illustrating the improved bat as completely folded.

In accordance with this invention, and referring particularly to the drawing, a cotton or other fibrous bat 1 is first formed in a perfectly flat condition, and another bat 2 of tough fibrous material, such as jute, is similarly formed and deposited upon the cotton bat 1. The two superposed bats are then preferably passed and compressed between rollers 3, which cause the fibers in the abutting faces of the two bats to interweave with one another to some extent, so that they will adhere to one another, and therefore be more easily handled in successive operations.

The side edge or marginal portions of the combined bat are then folded over upon the same face of the bat, that is upon the jute or tough fibrous bat, as shown in Fig. 6, the folded edge portions overlapping with one another somewhat as will be observed from Fig. 6. The bat when completely folded is shown in Fig. 7, and the folded bat is preferably then further compressed or rolled by pressure applied to opposite faces thereof, which further interknits or interlocks the fibers or abutting layers in such a manner that they will adhere while the bat is being handled for upholstering purposes.

The bat of loose, tough fibers which forms the core or lining of the combined bat, gives the finished bat great tensile strength, so that it may be used directly without the use of a burlap backing, and is sufficiently elastic to accommodate itself to all undulations of the surface to be covered thereby. The finished bat has great strength to resist the punching of holes therein by any projections on the surface being covered, and the cotton outer surface gives the bat a good appearance which will not show through the usual coverings or present an unsightly appearance if the covering is thin.

The cotton or outer bat is preferably some-

what wider than the inner bat of jute or the like having the long, tough fibers, and the marginal edge strips of the cotton bat preferably taper in thickness outwardly, that is, they are made thinner towards the extreme side edges, as shown in Figs. 3 and 4, and then when the bat is folded as shown in Figs. 6 and 7, the tapered edges which overlap will not form ridges in the finished bat, and the finished bat will be of substantially uniform thickness across its entire width.

In casket work, such a combined bat of cotton with a jute core is cheaper than an all cotton bat, and since the cotton forms the exterior covering of the combined bat, it presents an attractive, white appearance, which will not show under silk linings.

The finished bats may be made entirely by machinery, of any desired widths, and folded and rolled in long strips or rolls. Consequently, the cost of manufacture is relatively low and quantity production is feasible. The projecting side edges of the cotton bat, as shown in Figs. 4 and 5, cover the jute or other core after the combined bat has been folded, and the finished bat, due to interlocking of the overlapping cotton, is in reality a continuous tubular cotton bat, completely enclosing a thin, flat, elastic and strong core of tough fibers. This combined tubular bat may also be turned or further folded any number of times, and the more it is turned, the stronger it becomes.

Each component bat may be separately formed in any suitable or usual manner, such as by first carding or garnetting the fibers, during which the fibers are straightened and then deposited in a mat or continuous layer, with the fibers criss-crossing one another to give the bat maximum strength.

It will be obvious that various changes in the details, which have been herein described and illustrated in order to explain the nature of the invention, may be made by those skilled in the art within the principle and scope of the invention as expressed in the appended claims.

Claims:—

1. A bat for use in upholstery and the like, comprising a bat of cotton, a narrower bat of loose, tough fibers superposed upon the cotton bat, and the edges of the combined bat being folded over towards and overlapping one another.

2. A bat for use in upholstery and the like, comprising a loose fibrous bat of one material superposed upon a wider bat of another and different fibrous material, and the combined bat folded to encase the first mentioned bat in the second with the edges of the wider bat overlapping one another.

3. The method of forming bats for upholstery and the like, which comprises depositing a bat of one loose fibrous material upon a wider bat of another and different

fibrous material, and folding over the sides of the two bats together until at least the lower bat encloses the upper bat.

4. The method of forming bats for upholstery and the like, which comprises depositing a bat of one loose fibrous material upon a wider bat of another and different fibrous material, folding over the sides of the two bats together until at least the lower bat encloses the upper bat, and compressing the folded bat from face to face to intermesh the fibers of the abutting surfaces of the bats.

5. The method of forming bats for upholstery and the like, which comprises depositing a bat of one loose, fibrous material upon a wider bat of another and different fibrous material, compressing the bats together face to face, folding over the sides of the two bats together until at least the lower bat encloses the upper bat, and compressing the folded bat from face to face to intermesh the fibers of the abutting surfaces of the bats.

6. The method of forming bats for upholstery and the like, which comprises depositing a jute fiber bat upon a wider cotton bat, and folding the side portions of the double bat thus formed towards one another with the wider cotton bat edges overlapping one another.

7. A bat for use in upholstery and the like, comprising a bat of cotton, a narrower bat of loose, tough fibers and of approximately uniform thickness, superposed upon the cotton bat, and the edges of the combined bat being folded over towards and overlapping one another.

8. A bat for use in upholstery and the like, comprising a cotton bat having encased therein a reinforcing bat of loose, tough fibers and of approximately uniform thickness, the tough fibers running in different directions in the bat, and the fibers of one bat being interlaced with those of the other at their abutting surfaces by compression of the bats.

9. A bat for use in upholstery and the like, comprising a loose fibrous bat of one material and of approximately uniform thickness, superposed upon a wider bat of another and different fibrous material and of approximately uniform thickness and the combined bat folded to encase the first mentioned bat in the second with the edges of the wider bat overlapping one another.

10. The method of forming bats for upholstery and the like, which comprises depositing a bat of one loose fibrous material of approximately uniform thickness upon a wider bat of another and different fibrous material of approximately uniform thickness, and folding over the sides of the two bats together until at least the lower bat encloses the upper bat.

11. The method of forming bats for upholstery and the like, which comprises depositing a bat of one loose fibrous material

of approximately uniform thickness upon a wider bat of another and different fibrous material of approximately uniform thickness, folding over the sides of the two bats together until at least the lower bat encloses the upper bat, and compressing the folded bat from face to face to intermesh the fibers of the abutting surfaces of the bats.

12. A bat for use in upholstery and the like, comprising a loose fibrous bat of one material superposed upon a wider bat of another and different fibrous material, and the combined bat folded to encase the first mentioned bat in the second with the edges of the wider bat overlapping one another, the fibers of said one material running in different directions in the bat, whereby the strength of the combined bat to resist tearing will be a maximum.
